HYDRAULIC POWER TRANSMISSION WITH
FLOW CONTROL BY-PASS VALVE

Ralph L. Tweedale, Birmingham, Mich., assignor
to Vickers Incorporated, Detroit, Mich., a corporation of Michigan

Application December 26, 1944, Serial No. 569,827

13 Claims. (Cl. 60—53)

1

This invention relates to power transmissions, particularly to those of the type comprising two or more fluid pressure energy translating devices, one of which may function as a pump and another as a fluid motor.

The invention is particularly adapted for use with a reeling device and has been illustrated as applied to a mechanism of this character although it will be understood that the invention is equally adaptable to other applications.

When a strip of material is being wound upon a reel and being fed to the reel at a constant speed, it is necessary as the diameter of the reeled material increases to decrease the speed of the reel. Likewise, if a constant tension is maintained on the reeled material increasing in diameter, a progressively increasing torque must be applied to the reel.

In a hydraulic transmission for driving a reel comprising a fixed displacement pump and motor driving the reel, the product of pressure and volume should be a constant. As the material being wound upon the reel increases in diameter and the pressure rises, the volume of fluid to the motor driving the reel should decrease, not along a straight-line relation but by a hyperbolic relation.

It is an object of the present invention to provide, for use in a hydraulic transmission comprising a fixed displacement pump and motor for driving a reel, a flow regulating device which will maintain a constant uniform tension upon a strip of material being wound upon a reel as it increases in diameter.

It is also an object of this invention to provide for use in a hydraulic transmission, as above mentioned, a pressure responsive throttle valve constructed and designed to give a predetermined increased bleed-off of pump volume in response to an increase in motor pressure to establish the required hyperbolic relationship between motor pressure and flow through, or displacement of, the motor.

It is a further object of this invention to provide for use in a hydraulic transmission, as above mentioned, a simply constructed and economically manufactured flow regulating valve which will decrease the speed of the motor driving a reel in response to an increase of motor pressure and torque as the diameter of the material being wound on the reel increases.

Further objects and advantages of the present invention will be apparent from the following description, reference being had to the accompany-

2

ing drawing wherein a preferred form of the present invention is clearly shown.

In the drawing:

Figure 1 is a diagrammatic view of a power transmission system incorporating a preferred form of the present invention.

Figure 2 is a plot of fluid flow changes with pressure changes.

Figure 3 is a plot of valve opening changes with pressure changes.

Referring now to Figure 1, there is illustrated a pump 10 of the fixed displacement type, which may be driven by an electric motor 11, which has a suction conduit 12 connected to a tank 14 and a pump delivery conduit 16 connected to the inlet port 18 of a flow regulating valve 20 which also has an outlet port 22, a bypass port 24 and, in its preferred form, a venting port 26. Connected to the outlet port 22 of valve 20 is a supply conduit 28 connected to a motor 30 having also a return conduit 32 connected to the tank 14. The motor 30 drives a reel 34 used for the purpose of winding a strip of material thereon.

A conduit 36 connects the venting port 26 with a suitable two-way valve 38, and a conduit 40 connects valve 38 with the tank 14. The two-way valve 38, when closed, will hold the valve 20 closed to direct fluid from pump 10 to motor 30 to start said motor, or, when opened, will open valve 20 completely to unload pump 10 to tank 14 to stop motor 30.

The flow regulating valve 20 is comprised of a housing having a longitudinal stepped bore 42 communicating with the inlet port 18, outlet port 22, bypass port 24 and venting port 26. Shiftable within bore 42 is a throttle valve 44 comprising a piston 46 connected to which is a stem 48 tapered at a point 50 to rest on a seat 52 formed within the bore 42. The valve 44 has tapered grooves 53 and a centrally drilled passageway 55 and a restricted passageway 56 in the piston 46.

Valve 44 when positioned in bore 42 forms a lower chamber 58 on the underside of piston 46 and an upper chamber 60 between the upper side of piston 46 and the inner side of an end cap 62. The passageway 56 in piston 46 forms a communication between chamber 58 and chamber 60. A spring 64 of predetermined light tension is located in the upper chamber 60 abutting the upper side of piston 46 and the inner side of end cap 62 and tends to bias valve 44 to the closed position.

When seated, the valve 44 blocks communication between inlet port 18 and bypass port 24.

The tapered grooves 53 of stem 48 are designed to bypass an increasing amount of fluid from pump 10 to tank 14 as it gradually raises from its seat 52 in response to pressure at motor 30. An exhaust chamber 65 formed in bore 42 between seat 52 and bypass port 24 together with a conduit 57 provide passage for fluid bypassed through the seat 52.

A pilot valve 66 is located in the upper chamber 60 and has a conical surface 68 at one end designed to seat on the upper end of passageway 54 of valve 44 and has a centrally drilled passageway 70. A spring 74 of predetermined resistance, abutting the upper end of pilot valve 66 and an adjustable screw 76, and located within a bore 75 of end cap 62, tends to bias valve 66 to the seated position. The pilot valve 66 is shiftable within bore 75. Passageway 70, connecting with bypass port 24, tends to act as a drain for any fluid seepage in bore 75 which would tend to disturb the effective operation of pilot valve 66. A protective cap 78 is threaded over the adjustable screw 76 to protect the setting of spring 74 which is originally set according to the diameter of reel 34 in order to provide the correct motor speed required during the winding operation.

In operation, with the pump 10 running, the two-way valve 38 is shifted to block communication between venting port 26 of valve 20 and tank 14. This blocks egress from chamber 60, and the pressure therein will equalize with that in chamber 58, thus permitting spring 64 to close valve 48. Fluid from tank 14 is withdrawn through conduit 12 by pump 10 and delivered into conduit 16 to the inlet port 18 of valve 20 and through outlet port 22 and conduit 28 to motor 30 which drives reel 34, the return fluid from motor 30 returning to tank 14 by means of conduit 32.

At this stage of the operation, because the small diameter of the material winding on reel 34 creates a low torque, the pressure in conduits 16 and 28 is low, and the reel is being operated by motor 30 at the highest possible speed. Fluid under pressure entering inlet port 18 of valve 20 is blocked from communication with bypass port 24 because of valve 50 being seated on seat 52. Fluid under pressure entering chamber 58 also enters upper chamber 60 by means of passageway 56 in piston 46 and acts on pilot valve 66 at surface 68. Chamber 60 is blocked from communication with bypass port 24 because of pilot valve 66 resting on the seat formed in the upper end of passageway 54 in valve 44. The force exerted on the upper side of piston 46 is greater than the force exerted on its underside because of a slightly greater area on the upper side of piston 46, tending to keep valve 50 seated.

As the diameter of the winding strip of material increases on reel 34 causing an increase in torque of motor 30 which causes an increase in pressure, this increase of pressure will also react on pilot valve 66 at surface 68 by means of passageway 56 in piston 46. With each increase of pressure, the resistance of spring 74 will be slightly overcome, and pilot valve 66 will raise, unseating valve 68. Fluid under pressure from pump 10 in chambers 58 and 60 is able to leave chamber 60 faster through passageway 54 of valve 44 than fluid under pressure can enter chamber 60 from chamber 58 through passageway 56. This causes a pressure drop in chamber 60, and, the pressure in chamber 58 on the underside of piston 46 being greater than the pressure 75

in chamber 60 on the upper side of piston 46, valve 44 will raise slightly, unseating valve 50 from seat 52, allowing fluid to be bypassed at a predetermined rate from pump 10 to tank 14 through seat 52, exhaust chamber 65, bypass port 24 and conduit 67.

As the pressure at motor 30, which is equal to the pressure at pump 10, continues to increase because of the increase in diameter of the strip of material being wound on reel 34, the same pressure increase will react on pilot valve 66 permitting valve 44 to continue to raise. The tapered grooves 53 of valve 44 are designed to permit an increasing amount of fluid from pump 10 to be bypassed to tank 14 as the pressure at motor 30 continues to increase. As the amount of fluid being bypassed from pump 10 to tank 14 increases, the speed of motor 30 is proportionately decreased, thus maintaining a constant tension upon the strip of material being wound upon reel 34.

Considering the operation in more detail, it should be noted that pilot valve 66 rests upon main valve 44 so that the position of main valve 44 effectively determines the compression of pilot valve spring 74. In other words, as main valve 44 lifts, it progressively increases the compression of pilot valve spring 74 and thus raises the pressure at which pilot valve 66 opens. The curvature of the tapered grooves 53 is predetermined in accordance with the characteristics of spring 74 and the laws of fluid flow so that for any pressure in motor conduit 28 there will be a predetermined area of opening through the valve seat 52. This is chosen so as to achieve the desired performance results as to the relationship between the speed of the motor 30 and the operating pressure thereof.

There is plotted in Figure 2 an example of a relationship between motor pressure and the volume of fluid bypassed through seat 52 which is in the general form of a hyperbola based on the relationship that the difference between the fixed pump displacement and the bypass volume when multiplied by the pressure equals a constant. Because the orifice formed by seat 52 and tapered grooves 53 is not subject to a constant pressure, the area of grooves 53 at any given position of valve 44 must be chosen to take this factor into account.

As illustrated in Figure 3 wherein the hyperbolic curve of Figure 2 has been shown in dotted lines, the amount of valve opening departs from the curve of bypass volume by a progressively increasing amount as the pressure increases. Thus, taking into account the factor of increased pressure impressed across the valve orifice at greater openings of the valve 44, the curvature of grooves 53 can be made to produce any desired motor performance as the real diameter progressively increases.

Commonly it is desired to maintain uniform tension and uniform linear speed on the strip material, and this relationship is easily achieved by proper computation as to the conformation of the grooves 53. It will thus be seen that any desired relationship between reel speed and torque may be easily maintained throughout a wide range of reel diameters.

When the winding operation has been completed, the control handle of valve 38 is shifted to connect venting port 26 of valve 20 with tank 14 by means of conduits 36 and 40. Fluid under pressure entering chamber 58 and chamber 60 is permitted to leave chamber 60 by way of port

26 faster than it can enter chamber 60 due to the restricted passageway 56 in piston 46 which causes a pressure drop in chamber 60 and completely opens valve 20 which will unload pump 10 to tank 14 and thus stop motor 30.

While the form of embodiment of the invention as herein disclosed constitutes a preferred form, it is to be understood that other forms might be adopted, all coming within the scope of the claims which follow. Although the invention has been shown to be suitable and adaptable for use in a hydraulic transmission for driving a reel comprising a fixed displacement pump and motor driving the reel, it may be successfully applied in a similar hydraulic transmission for driving any load device where similar results are desired. Thus, the invention may be applied in a hydraulic transmission containing a fixed displacement pump and motor driving a load device where it is desired to drive the load device at varying and progressive speeds and torques but at substantially constant horsepower, or where a desired relationship between the speed of the driven load device and torque of the same is required in spite of a continuously varying load resistance, or where the speed of the driven load device must change in a predetermined relationship in response to changes in torque.

Certain subject matter in common with the present invention is disclosed and claimed in a copending application of Warren Brown, Serial No. 569,826, filed December 26, 1944, title, Power transmission.

What is claimed is as follows:

1. In a hydraulic power transmission system for driving a reel and having a fixed displacement pump and a fixed displacement fluid motor, a valve comprising a throttle as the sole restrictive means to bypass a variable portion of the pump delivery around the motor and having a predetermined relationship between its positional adjustment and its resultant opening area, and resiliently-loaded means responsive to the pressure required to drive the motor for controlling the positional adjustment of the throttle.

2. In a hydraulic power transmission system for driving a reel and having a fixed displacement pump and a fixed displacement fluid motor, a valve comprising a throttle the entrance to which is in open and direct communication with the motor, and arranged to bypass a variable portion of the pump delivery around the motor and having a predetermined relationship between its positional adjustment and its resultant opening area, and resiliently-loaded means responsive to the pressure required to drive the motor for controlling the positional adjustment of the throttle.

3. In a hydraulic power transmission system for driving a reel and having a fixed displacement pump and a fixed displacement fluid motor, a valve comprising a throttle the entrance to which is in open and direct communication with the motor, and arranged as the sole restrictive means to bypass a variable portion of the pump delivery around the motor and having a predetermined relationship between its positional adjustment and its resultant opening area, and resiliently-loaded means responsive to the pressure required to drive the motor for controlling the positional adjustment of the throttle.

4. In a hydraulic power transmission system for driving a reel and having a fixed displacement pump and a fixed displacement fluid motor, a valve comprising a throttle as the sole restrictive

means to bypass a variable portion of the pump delivery around the motor and having a predetermined relationship between its positional adjustment and its resultant opening area, and a resiliently-loaded pilot valve responsive to the pressure required to drive the motor for controlling the positional adjustment of the throttle.

5. In a hydraulic power transmission system for driving a reel and having a fixed displacement pump and a fixed displacement fluid motor, a valve comprising a throttle as the sole restrictive means to bypass a variable portion of the pump delivery around the motor and having a predetermined relationship between its positional adjustment and its resultant opening area, and a resiliently-loaded pilot valve responsive to the pressure required to drive the motor, the pressure response of which is varied with the positional adjustment of the throttle, said pilot valve opening to cause an increased opening of the throttle valve.

6. In a hydraulic power transmission system for driving a reel and having a fixed displacement pump and a fixed displacement fluid motor, a valve comprising a throttle as the sole restrictive means to bypass a variable portion of the pump delivery around the motor and having a predetermined relationship between its positional adjustment and its resultant opening area, and a resiliently-loaded pilot valve responsive to the pressure required to drive the motor, the pressure response of which is varied with the positional adjustment of the throttle, said pilot valve opening to cause an increased opening of the throttle valve whereby the volume of fluid to the motor decreases with increases of pressure at the motor in hyperbolic relation.

7. In a hydraulic power transmission system for driving a load device at speeds which are varied in response to changes in torque and having a fixed displacement fluid pump and motor, a valve comprising a throttle the entrance to which is in open and direct communication with the motor and arranged to bypass a variable portion of the pump delivery around the motor, a longitudinal stepped bore within which the throttle is shiftable and forming an upper and lower chamber in communication with each other, said throttle having a centrally drilled passageway, one end of which forms a seat, and a resiliently-loaded pilot valve responsive to the pressure required to drive the motor and coacting with said seat, the pressure response of which is varied with the positional adjustment of the throttle, said pilot valve controlling the seat opening for controlling the opening of the throttle valve.

8. In a hydraulic power transmission system for driving a load device at speeds which are varied in response to changes in torque and having a fixed displacement fluid pump and motor, a valve having an inlet port, a motor port and an exhaust port and comprising a throttle the entrance to which is in open and direct communication with the motor and arranged to bypass a variable portion of the pump delivery around the motor, a longitudinal stepped bore within which the throttle is shiftable and forming an upper and lower chamber in communication with each other, said throttle having a centrally drilled passageway connecting the upper chamber and exhaust port, one end of which forms a seat, and a resiliently-loaded pilot valve responsive to the pressure required to drive the motor and coacting with said seat, the pressure response of which is varied with the positional ad-

justment of the throttle, said pilot valve controlling the seat opening for controlling the opening of the throttle valve.

9. In a hydraulic power transmission system for driving a load device at speeds which are varied in response to changes in torque and having a fixed displacement fluid pump and motor, a valve having an inlet port, a motor port and an exhaust port and a venting port to which is connected a manually-operated valve to direct fluid from the pump to the motor to start and operate said motor or to completely bypass the motor and unload the pump in order to stop the motor, and comprising a throttle the entrance to which is in open and direct communication with the motor and arranged to bypass a variable portion of the pump delivery around the motor, a longitudinal stepped bore within which the throttle is shiftable and forming an upper and lower chamber in communication with each other, said throttle having a centrally drilled passageway connecting the upper chamber and exhaust port, one end of which forms a seat, and a resiliently-loaded pilot valve responsive to the pressure required to drive the motor and coacting with said seat, the pressure response of which is varied with the positional adjustment of the throttle, said pilot valve controlling the opening of the seat for controlling the opening of the throttle valve.

10. In a hydraulic power transmission system for driving a load device at varying speeds and torques but at substantially constant horsepower and having a fixed displacement pump and a fixed displacement fluid motor, a valve comprising a throttle as the sole restrictive means to bypass a variable portion of the pump delivery around the motor and having a predetermined relationship between its positional adjustment and its resultant opening area, and resiliently-loaded means responsive to the pressure required to drive the motor for controlling the positional adjustment of the throttle.

11. In a hydraulic power transmission system for driving a load device at speeds which are varied in response to changes in torque and having a fixed displacement pump and a fixed displacement fluid motor, a valve comprising a throttle as the sole restrictive means to bypass a variable portion of the pump delivery around the motor and having a predetermined relationship between its positional adjustment and its resultant opening area, and resiliently-loaded means re-

sponsive to the pressure required to drive the motor for controlling the positional adjustment of the throttle.

12. In a hydraulic power transmission system for driving a load device at varying speeds and torques but at substantially constant horsepower and having a fixed displacement fluid pump and motor, a valve comprising a throttle the entrance to which is in open and direct communication with the motor and arranged to bypass a variable portion of the pump delivery around the motor, a longitudinal stepped bore within which the throttle is shiftable and forming an upper and lower chamber in communication with each other, said throttle having a centrally drilled passageway, one end of which forms a seat, and a resiliently-loaded pilot valve responsive to the pressure required to drive the motor and coacting with said seat, the pressure response of which is varied with the positional adjustment of the throttle, said pilot valve controlling the opening of the seat for controlling the opening of the throttle valve.

13. In a hydraulic power transmission system for driving a load device at speeds which are varied in response to changes in torque and having a fixed displacement fluid pump and motor, a valve comprising a throttle the entrance to which is in open and direct communication with the motor and arranged to bypass a variable portion of the pump delivery around the motor, a longitudinal stepped bore within which the throttle is shiftable and forming an upper and lower chamber in communication with each other, said throttle having a centrally drilled passageway, one end of which forms a seat, and a resiliently-loaded pilot valve responsive to the pressure required to drive the motor and coacting with said seat, the pressure response of which is varied with the positional adjustment of the throttle, said pilot valve controlling the opening of the seat for controlling the opening of the throttle valve.
